(57) **CLAIM**

The ornamental design for a quilted band, as shown and described.

DESCRIPTION

FIG. 1 is a front perspective view of the present invention.

FIG. 2 is a top plan view of FIG. 1.

FIG. 3 is a front elevation view of FIG. 1, noting the side view of the claimed region.

FIG. 4 is a left side elevation view of FIG. 1.

FIG. 5 is a right side elevation view of FIG. 1.

FIG. 6 is a rear elevation view of FIG. 1.

FIG. 7 is a bottom plan view of FIG. 1; and,

FIG. 8 is a top plan sectional view along section 8-8 in FIG. 3, noting the quilted band portion from a top plan view.

The broken lines shown immediately adjacent to the solid line portions of the drawings illustrate the boundaries of the claim and do not form a part of the claimed design. Other broken lines in the drawings illustrate portions of the quilted band that form no part of the claimed design and a gemstone and setting that are environmental and form no part of the claimed design.
